CARBON INTERLEAVED RECORD ASSEMBLY

James Gordon Kerr, Washington, D. C., assignor to Moore Business Forms, Inc., a corporation of Delaware

Application May 19, 1944, Serial No. 536,291

5 Claims. (Cl. 282—11.5)

This invention relates to improvements in manifolding assemblies of the long continuous traveler type, wherein long continuous record strips are interleaved in transfer relation with long continuous transfer strips whereby inscriptions made upon the top or original transfer strip are transferred to the underlying record strip or strips.

It is a general object of the invention to provide in manifolding assemblies of the class mentioned, an improved construction and arrangement whereby the record and transfer leaves of the assembly sets after having been inscribed in a typewriter or other writing machine, may be quickly and easily separated from each other, and at the same time, provision is made for making corrections, erasures, additions, and so forth, on the underlying record strips while the assembly is in writing position in the machine, thus avoiding removal of the assembly from the machine when it becomes necessary to make such corrections, erasures, or similar alterations.

Another object of the invention is to provide in a manifolding assembly of the class mentioned an improved construction and arrangement of the record and transfer strips, whereby when the assembly strips have been severed from the assembly binding means for the purpose of making corrections, erasures, or other alterations, selective grip formations such as selective grip tabs are provided on certain of the strips, such as the transfer strips, which can be used for selectively separating the record and transfer leaves of a severed inscribed set.

A further object of the invention is to provide in a manifolding assembly of the class mentioned an improved structure and arrangement whereby the record and transfer leaves of a severed inscribed set can be quickly and easily separated from each other by means of a selective grip arrangement, either when the leaves of the set are bound together in a binding stub or when they have been severed from such binding stub in the typewriting machine, so as to permit the sheets to be separated for the purpose of making erasures, corrections, and so forth, on the underlying record strips.

According to a feature of improvement in the particular embodiment of the invention herein disclosed, both the record and transfer strips of the assembly are provided with two transverse weakened severance lines at each form length interval, such lines being longitudinally spaced short distances so as to form binding stubs by which the record and transfer strips are bound

together at form length intervals, the inner of such weakened severance lines of the transfer strips having outwardly deviating portions so as to provide outwardly protruding grip tabs on the

6 transfer leaves when severance is made along such inner weakened lines for the purpose of permitting the leaves to be separated for making erasures, corrections, or other alterations, or for inspection.

10 Other objects and advantages of the invention will be in part pointed out in the following detailed disclosure of an illustrative but preferred embodiment of the invention, and will be in part obvious as the disclosure proceeds.

15 The invention accordingly comprises the features of construction, combination of elements, and arrangement of parts, which will be exemplified in the construction hereinafter set forth and the scope of the application of which will be indicated in the claims.

20 For a more complete disclosure of the nature, objects and advantages of the invention, reference is had to the following detailed description of the illustrative preferred embodiment, and to the accompanying drawing in which:

Fig. 1 is a perspective view of a manifolding or record assembly embodying the invention;

25 Fig. 2 is a partially diagrammatic enlarged perspective view of a set of record and transfer leaves severed from the complete assembly; and

30 Fig. 3 is a perspective view of a severed set of record and transfer leaves that have been severed from the binding stub.

35 Referring to the drawing for a detailed description of the embodiment of the invention there shown, the complete manifolding assembly 5 as shown in Fig. 1 embodies a plurality of long continuous record strips 6 with which one or more transfer or carbon strips 7 are interleaved in superposed transfer relation so that inscriptions made upon the top or original record strip 6 are transferred to the underlying or copy record strips. In the illustrative embodiment shown there are three such record strips 6 and two interleaved transfer strips 7, but it will be understood that the assembly may be made up of any desired number of record strips with sufficient transfer strips to transfer the inscriptions to each of the copy record strips. In some cases the complete assembly may include only two record strips with a single interleaved transfer strip. Each record strip will ordinarily be provided with a series of blank forms 8 repeated at leaf or form length intervals throughout the length of each record strip. These blank forms are arranged

in superposed aligned or registered relation in the superposed record strips so that entries made upon the top forms will be registered in their proper relation in the underlying forms. The assembled strips are preferably zigzag folded at 5 form length intervals into a zigzag supply pack 9. As shown, the transfer strips 7 are coated with carbon or similar transfer material only on their under surfaces as indicated at 10.

Each record strip 8 is formed with transverse 10 weakened severance lines 11 longitudinally spaced at form length or leaf length intervals, thus dividing each strip into a longitudinal series of record leaves or form lengths 6'. Similarly, the transfer strips 7 are provided with a series of 15 longitudinally spaced transverse weakened severance lines 12 which may be formed the same as those in the record strips and forming series of transfer leaves 7'. These weakened severance lines 11 and 12 may be of the same construction 20 and arrangement as the weakened severance lines disclosed in the prior Kerr Patent 2,300,255, is-sued October 27, 1942, or they may be of other known structure.

Respectively spaced short distances from the 25 weakened severance lines 11 of the record strips, are transverse weakened severance lines 13 thus forming a series of short binding stubs 14 spaced at form length intervals along the respective record strips. Similar transverse weakened severance lines 15 are provided in each of the transfer strips and respectively similarly spaced from the severance lines 12 thereof so as to provide binding stubs 16 of the transfer strips longitudinally spaced at form length intervals and respectively arranged in superposed relation with the binding stubs 14. The record and transfer strips are bound together at form length intervals at the binding stubs 14 and 16 by any appropriate binding means such, for example, as the binding 30 staples 17 shown. This arrangement provides a longitudinal series of sets of record and transfer leaves, the leaves of each set being bound together by the respective binders 17. It will thus be understood that a leaf set comprises the sections of record and transfer strips between successive or adjacent severance lines 11 and 12, and that the record leaves 6' and transfer leaves 7' of the sets comprise the short sections of strips which are 35 bound together by the respective bindings.

It will be noticed that each of the severance lines 15 of the transfer strips has a forwardly deviating portion 15a extending transversely of the adjacent binding stub 16. This deviating part 15a extends to the adjacent edge of the transfer leaf or stub thereof in which it is located, preferably as shown intersecting the adjacent severance line 12. This deviating line 15a thus delineates one edge of a grip tab 18, the purpose and function of which are later described.

In order to provide selective grip formations remote from the bindings 17, notches 19 are formed in the edges of the respective transfer leaves 7' through which adjacent marginal portions of the record leaves can be gripped without at the same time gripping the transfer leaves. These selective grip formations may be constructed and arranged in any desired manner so long as they are positioned remote from the respective bindings 17. In the embodiment shown these selective grip formations may be formed as disclosed in the Conklin Patent No. 2,083,295, issued June 8, 1937, by providing forwardly deviating portions in the weakened severance lines 12 so that when the strips are severed along such 40

lines the notches 19 are formed at one severed edge while at the adjacent severed edge the tongues 20 are formed such as shown at the right in Fig. 2. These selective grip formations may be formed in any other known manner. If the tongues 20 are formed as described, the weakened severance lines 12 of the transfer strips may be continued across the bases of the tongues as at 45 12' in Fig. 2, or these weakened lines or perforations may be omitted at the bases of the tongues as shown in the Conklin patent referred to.

It will be understood that the disclosure of the drawing, particularly that of Fig. 2, is partially diagrammatic, the record and transfer leaves being considerably separated from their normal positions in order to disclose the structure and arrangement more clearly, while the fastening devices 11 are shown as abnormally elongated. It will also be understood that the strips and leaves in their normal operative position lie in close face to face contacting relation so that the inscriptions made upon the upper forms will be transferred to the lower forms in the manner well known in the art.

In using the improved manifolding assembly as above disclosed, the forward end of the assembly will be entered in the writing machine such as over the cylindrical platen of a typewriter, and the inscriptions will be entered on the blank forms of a set of leaves by operation of the writing machine. In their normal condition the forward ends of the leaves of a set will be bound together at their binding stubs 14 and 16 by the binders 17. But if it becomes necessary or desirable to separate the forward ends of the strips for the purpose of making corrections or erasures on the underlying forms or for any other purpose, this can be very readily accomplished merely by severing the forward ends of the leaves from the respective binding stubs. When thus severed the tops or forward ends of the leaves may be turned backwardly so as to expose the surfaces of the underlying forms and the inspections, erasures or corrections can then be readily made.

In case no erasures or corrections become necessary during the inscription of a set of forms, the set completely inscribed will be fed forwardly in the machine and severed from the complete assembly along the adjacent weakened severance lines 11, 12, or the successive inscribed sets may be run continuously without severance. This severance will form the marginal notches 19 to provide the selective grip formation remote from the binding as above described. The set of inscribed record and transfer leaves thus severed forms a unit in which the leaves are bound together by the binders 17 as shown diagrammatically in Fig. 2. The inscribed record leaves of this unit can be readily separated from the transfer leaves 50 merely by gripping the forward end of the unit at the binding and at the same time gripping the rear end thereof at the selective grip formation provided by the notches 19, and then exerting a quick pull or snap action whereupon the record leaves 6' will be severed along the weakened lines 55 13 thereof and at the same time separated from interleaved relation with the transfer leaves 7' which will remain attached to the binding. In order that this severing and separating action 60 may be accomplished without danger of severing the transfer sheets at the same time along their severance lines 15 which are positioned inwardly with reference to the ends of the set of forms, said lines 15 are weakened to a less extent than 65 70 75 76 are the lines 13 of the record leaves. In other

words, the weakened lines of the record leaves are weaker than those of the transfer leaves in order to facilitate the selective separation.

In cases where erasures or corrections have been found necessary and the binding stubs of a severed set of leaves removed as above indicated, it will be seen that the record and transfer leaves cannot then be separated from each other as above described. However, the severance of the binding stubs as described, will form the forwardly projecting grip tabs 18 of the transfer leaves in the manner above indicated. The set of severed record and transfer leaves then assumes the condition as indicated in Fig. 3 wherein the forwardly projecting tabs 18 provide a selective grip for the transfer leaves, and the notches 19 form a selective grip for the record leaves. Thus, by selectively gripping the transfer leaves at one edge and selectively gripping the record leaves at a remote point, the record and transfer leaves may be very quickly and easily separated from each other.

Since certain changes may be made in the article herein described and different embodiments of the invention could be made without departing from the scope thereof, it is intended that all matter contained in the above description or shown in the accompanying drawing shall be interpreted as illustrative and not in a limiting sense.

The invention having thus been fully described, the following is claimed:

1. In a manifolding assembly in combination, a plurality of long continuous record and transfer strips assembled in transfer relation and having transverse weakened severance lines whereby the assembly may be severed into form lengths or leaf sets, longitudinally spaced binding means binding said strips together respectively adjacent to said weakened severance lines, supplemental transverse weakened severance lines in the said record and transfer strips for each said leaf set positioned respectively adjacent to and inside of said binding means providing for severance of the strips from the respective binding means whereby the strips may be separated to expose underlying strips for making erasures or for other purposes, and a selective grip formation in each leaf set remote from the respective binding means whereby certain of the leaves of a severed set may be selectively gripped to the exclusion of the others and severed along the corresponding said supplemental weakened severance lines which are weaker than the corresponding supplemental weakened lines of the other strips so as to facilitate selective severance, certain but not all of said supplemental weakened lines deviating outwardly from others of the set in which it is located to form selective grip tabs projecting outwardly from the severed leaf set remote from the said selective grip formation thereof, so as to provide for selective separation of the record and transfer leaves of the severed set after detachment thereof on said supplemental weakened severance lines.

2. In a manifolding assembly in combination, a plurality of long continuous record and transfer strips assembled in transfer relation and having transverse weakened severance lines whereby the assembly may be severed into form lengths or leaf sets, longitudinally spaced binding means binding said strips together respectively adjacent to said weakened severance lines, supplemental transverse weakened severance lines respectively adjacent to and inside of said binding means pro-

viding for severance of the strips from the respective binding means whereby the strips may be separated to expose underlying strips for making erasures or for other purposes, and selective grip formations in each leaf set remote from the respective binding means whereby record leaves of a severed set may be selectively gripped to the exclusion of the transfer leaves thereof and severed along the corresponding supplemental weakened severance lines, the said supplemental weakened lines of the record strips being weaker than those of the transfer strips so as to facilitate selective severance, said supplemental weakened severance lines of the transfer strip respectively deviating from those of the record strips to provide selective grip tabs upon severance along said supplemental weakened lines for selective removal of the transfer leaves from the record leaves of a severed set.

3. In a manifolding assembly in combination, a plurality of long continuous record and transfer strips assembled in transfer relation and having transverse weakened severance lines whereby the assembly may be severed into form lengths or leaf sets, longitudinally spaced binding means binding said strips together respectively adjacent to said weakened severance lines, supplemental transverse weakened severance lines respectively adjacent to and inside of said binding means providing for severance of the strips from the respective binding means whereby the strips may be separated to expose underlying strips for making erasures or for other purposes, means including a selective grip formation in each said set of leaves whereby the record leaves of a severed set may be gripped to the exclusion of the transfer leaves thereof and selectively severed along certain of said supplemental weakened lines and to effect selective separation of the record and transfer leaves of a set severed from the assembly along said first mentioned weakened severance lines, and means including outwardly deviating parts of said supplemental weakened lines of the transfer strips for forming outwardly projecting selective grip tabs on the transfer leaves upon severance along said supplemental weakened severance lines, said outwardly projecting grip tabs on the transfer leaves being spaced from said selective grip formations of each said set of leaves whereby the record and transfer leaves can be respectively selectively gripped at said selective grip formations and at said grip tabs to effect selective separation thereof when the set of leaves is severed along said supplemental weakened lines.

4. A continuous transfer strip having at a plurality of longitudinally spaced intervals pairs of transverse weakened severance lines, the weakened lines of the pairs being respectively longitudinally spaced short distances to form a plurality of longitudinally spaced binding stubs, the inner weakened line of each of said pairs having an outwardly deviating part so as to form a projecting grip tab upon severance along said inner weakened line.

5. In a manifolding assembly, in combination, a plurality of long continuous record and transfer strips assembled in transfer relation and having transverse weakened severance lines whereby the assembly may be severed into detached form lengths or leaf sets, longitudinally spaced binding means binding said strips together respectively adjacent to said weakened severance lines so as to form bindings by which each respective detached set of record and transfer leaves may be held during selective separation of the record and trans-

fer leaves thereof, a selective grip formation in each of said leaf sets remote from the said binding thereof when the set is detached from the assembly along said weakened severance lines, and supplemental transverse weakened severance lines respectively adjacent to and inside of said binding means in each said leaf set of said long continuous strips providing for severance of the strips from the respective binding means whereby certain of the strips may be separated to expose 10 underlying strips for making erasures or for other purposes, certain of said supplemental weakened lines of each leaf set, but less than the whole num-

ber thereof, providing in cooperation with the corresponding said selective grip formation, for selective separation from said binding of the corresponding leaves of the detached set, the remainder of said supplemental weakened lines of each leaf set respectively deviating outwardly from the others so as to provide selective grip tabs outwardly projecting from the detached leaf set remote from the said selective grip formation thereof, upon severance along said supplemental weakened lines.

JAMES GORDON KERR.
